CLOSURE FOR COLLAPSIBLE TUBES

Filed April 14, 1926

UNITED STATES PATENT OFFICE

ARTHUR E. SMITH, OF LOS ANGELES, CALIFORNIA

CLOSURE FOR COLLAPSIBLE TUBES

Application filed April 14, 1926. Serial No. 101,907.

This invention relates to devices for dispensing plastic materials.

The general object of the invention is to provide an improved closure for collapsible tubes.

A specific object of the invention is to provide an improved closure for a collapsible tube wherein the closure includes an automatic valve.

10 An additional object of the invention is to provide a closure cap for collapsible tubes wherein the cap is made of rubber which has a valve slit cut therein after the cap is vulcanized.

15 An additional object of the invention is to provide a threaded rubber cap having a peripheral fin for engaging the end of a collapsible tube.

Other objects of the invention will be apparent from the following description taken in connection with the accompanying drawings wherein:

Fig. 1 is a perspective view showing the use of my invention;

25 Fig. 2 is a central sectional view partly in elevation showing my improved cap;

Fig. 3 is a view similar to Fig. 2 showing the valve open;

30 Fig. 4 is a sectional view of my improved cap;

Fig. 5 is a front end view of the cap;

Fig. 6 is an end view; and

35 Fig. 7 is a sectional view showing a slight modification of my improved cap;

Fig. 8 is an end view of a further modification;

Fig. 9 is a section on line 9—9, Fig. 8;

40 Figs. 10 and 11 are sectional and end views respectively of an additional modification, and

Fig. 12 is a sectional view of another modification.

Referring to the drawing by reference characters, I have shown my invention in connection with a collapsible tube shown at 10. In the following description, I will describe my invention as used in connection with collapsible tubes and particularly for the purpose of dispensing dental preparations, although it will be understood that the device

is not limited to this particular use, but may be used in dispensing other plastic substances which flow more or less freely and which are not sticky and which do not coagulate.

Referring again to the drawing, the collapsible tube is provided with a conical end portion 11 having a collar 12 integral therewith. This collar 12 is provided with external threads 14, as is usually the case.

A closure embodying the features of my invention is shown generally at 15. It comprises a body having an annular portion 16 and an end portion 17. The closure is provided with internal threads which mate with the threads 14 previously described. The annular portion 16 is beveled as at 18 and this beveled portion provides a fin 19 which is highly flexible and which engages the adjacent portion of the conical end portion 11 to seal the closure tightly when in position.

The closure is shown as provided with a transversely extending boss 20. This boss is so arranged as to provide a transverse cavity 21 adjacent the inner face of the boss, as clearly shown at 21 in Figs. 2 and 4.

75 The closure is preferably made of a good grade of rubber and is vulcanized to provide the desired elastic properties. After the rubber is vulcanized, a slit 22 is cut through the boss in any desired manner. This slit extends longitudinally of the boss 20 and is preferably of a length equal to the length of the cavity 21.

80 In using the device the tube 10 is brought near a brush 25 and the tube 10 is then squeezed, thus causing the dental cream to pass through the valve slit 22 onto the brush. As soon as the pressure is removed, the valve automatically closes, due to the rigidity of the walls of the boss and the associated parts 85 and the slight amount of dental cream remaining in the slit is forced out due to the inherent resilient properties of the boss, so that a tight seal is provided for the cream 90 remaining within the tube.

95 In Figs. 6 and 7, I have shown a slight modification wherein the end portion of the closure is provided with a cylindrical boss 26 instead of with a transverse boss as previously described. This cylindrical boss is pro- 100

vided with a slit 27 and the operation is the same as that previously described.

In Figs. 8 and 9, I have shown the end 30 of the collapsible tube 10 as provided with a neck 31 which has a peripheral groove 32 thereon. The cap is shown at 33 and is provided with a peripheral bead 34 which fits the groove 32. The cap may have a fin 35 similar to the fin 19 previously described. The cap 33 is shown as provided with a boss 36 which has a slit 37 therein. The operation of this cap is also similar in all respects to those previously described.

In Figs. 10 and 11, I have shown the end 15 of the collapsible tube 10 at 38. This tube has a collar 39 thereon with a peripheral groove 40 and the cap 41 has a peripheral bead 42 which fits the groove 40. The outer surface of the end of the closure 41 is in the nature 20 of a relatively flat cone and this cone is slotted as at 42 to provide a valve opening. The operation of this modification is the same as those previously described.

In Fig. 12 a collapsible tube is shown at 43 having a neck 44 which has threads 45 thereon. A closure member is indicated at 46. This member is made of rubber and has a thickened end portion 47 which has a valve slit 48 therein. The cap has an end flange 49 thereon which fits against the neck 44 and is engaged by the retaining ring 50 which has a threaded sleeve 51 thereon which engages the threads 45. When the ring 50 is turned to position it will tightly hold the closure 46 35 against the end 44 of the tube 43. The modification functions in the same manner as those previously described.

From the foregoing description it will be apparent that I have provided an improved 40 closure for tubes containing plastic, free flowing materials, which closure can be economically manufactured and is highly efficient in use, and which satisfies the conditions necessary to produce a sanitary device.

Having thus described my invention, I 45 claim:

1. A collapsible tube comprising a body having a neck, said neck being provided with a peripheral groove therein, an end closure 50 fitted over said neck, said end closure being made of rubber and having a bead thereon fitting said groove, said closure having a thickened boss thereon, said boss having a slit cut therein, said slit serving as a valve, said closure having a fin thereon engaging the end of said tube.

2. A closure cap for a collapsible tube, comprising a body including an annular portion and an end portion extending across said annular portion, said end portion having a transverse cavity therein communicating with the interior of said annular portion, said end portion having a protuberance thereon and a slit extending longitudinally of said protuberance and cavity.

3. A closure cap for a collapsible tube, comprising a body including an annular portion and an end portion extending across said annular portion, said end portion having a transverse cavity therein communicating 70 with the interior of said annular portion, said end portion having a protuberance thereon and a slit extending longitudinally of said protuberance and cavity, said slit terminating short of the lateral surface of said protuberance.

In testimony whereof, I hereunto affix my signature.

ARTHUR E. SMITH.
